UNITED STATES PATENT OFFICE.

ANDREW CHRISTIANSON, OF BUTLER, PENNSYLVANIA, ASSIGNOR TO
STANDARD STEEL CAR COMPANY, OF PITTSBURG, PENNSYLVANIA, A
CORPORATION OF PENNSYLVANIA.

METALLIC COMPARTMENT CONSTRUCTION FOR PASSENGER AND LIKE CARS.

No. 854,406.

Specification of Letters Patent.

Patented May 21, 1907.

Application filed September 7, 1906. Serial No. 333,622.

To all whom it may concern:

Be it known that I, ANDREW CHRISTIANSON, a resident of Butler, in the county of Butler and State of Pennsylvania, have invented a new and useful Improvement in Metallic Compartment Construction for Passenger and Like Cars; and I do hereby declare the following to be a full, clear, and exact description thereof.

10 This invention relates to metallic railway cars, and more especially to passenger, mail, baggage and express cars.

The object of the invention is to provide a construction for the ends of cars providing 15 waiting and retiring rooms, and the like, and which is so built up as to greatly reduce the number of parts employed, as well as the weight of the car.

20 The invention consists of the construction and arrangement of parts hereinafter described and claimed.

In the accompanying drawings, Figure 1 is a vertical section through the longitudinal center of a car showing my invention; Fig. 2 25 is a transverse section through the car; Fig. 3 is a horizontal section on the line 3-3', Fig. 1; and Figs. 4, 5 and 6 enlarged views of sections shown on Figs. 1 and 2.

As my invention has to do only with the 30 ends of the car where waiting or retiring rooms are generally provided, I have not thought it necessary to show the entire car, nor to show parts of the car ends not involving the invention.

35 The framing of the car may be of any desired construction, and most of it has been omitted from the drawings. The side frames are shown as comprising posts 1 of general channel form placed with their webs trans-

40 versely of the car and having inside and outside flanges. The end posts 2 are of a similar construction. All of these posts are shown as pressed shapes having wide outside flanges and comparatively narrow inside

45 flanges. Each side frame is provided with a bottom angle 4, a floor angle 5 and side plate 6, the latter being of channel shape having flanges of different widths and projecting downwardly and secured to the upper ends 50 of the posts. The carlines rest directly on these plates, comprising a lower deck member 7, an upper deck member 8, and a vertical connecting member 9. The lower deck

member is a curved plate of general channel form having the web vertical, a wide flange 55 at the top and a narrow flange at the bottom, and also integral flanges at both ends, that at the lower end being riveted to the web of the plate. The top deck member 8 is also of a pressed plate of channel form, placed with 60 its web vertical and having flanges of different widths. The vertical connecting member 9 has a wide web portion riveted directly to the webs of the top and bottom deck members and has a flange at its inner edge to 65 which is riveted the ventilator plate 10, the latter having its upper edge turned inwardly as at 11 and its lower edge turned outwardly as at 12, so as to form in effect a small plate girder. The upper deck plates are shown 70 at 13, the lower deck plate at 14, the outside finishing sheets at 15, and the floor plate at 16, but as these are not claimed in this application no special description of them is necessary. The drawing also shows a window sill at 17.

The present application relates entirely to details of construction for applying a compartment or compartments at the end or in the corner of the car and which is or are entirely or mostly composed of metal.

The compartments are indicated as a small salon 18 in one corner of the car and a corresponding salon 19 in the opposite corner of the car. The compartments have inner end 85 walls 20 and side walls 21. The compartments also have sloping tops 22 which meet the roof at the angles of the lower deck members and the vertical connecting members of the carlines. The interior finish at the end 90 of the car is shown at 24, being a sheet either of metal or special composition board or even of thin wood. This is secured to the inner flanges of the end posts 2, and near the roof is a transverse angle 25 placed with one leg vertical and on a line with the inner flanges of the posts 2 while the other leg projects toward the center of the car. This angle is attached to the end carline by means of a connection plate 27 riveted to the horizontal leg 95 of the angle 25 and to the lower flange of the end carline. The end finishing sheets 24 lap over the inner face of the vertical flange of the angle 25 while the ceiling sheets 28 lap over the lower face of the horizontal leg of 100 said angle. These sheets are secured in 105

place and a neat angle or corner finish is provided by means of the metallic molding 29, which as shown has two members substantially at right angles to each other, each member being provided on its face with a groove 30 in which are seated the heads of the tap screws 31 which pass through the molding and the edges of the inside finishing sheets, and into the legs of the angle 25. 5 Lock or friction washers 32 are seated in these grooves to prevent the screws from working loose. This molding is grooved or recessed on its back as shown at 33 so as to reduce the same in weight. 10 In order to secure the upper edges of the transverse partitions forming the inner end walls 20 of the compartments 18 and 19, I employ the special construction shown in Fig. 5, and which comprises a horizontal T 15 bar 35 having one flange of its head riveted to the web of a carline 7 and the other flange projecting downwardly while its leg projects toward the end of the car in line with the lower flange of the carline. The ceiling sheets 28 are lapped, the one over the lower face of the leg of the T bar, and the other over the lower face of the lower flange of the carline, while the two partition sheets 37 and 38 which are employed to give a finish to 20 both sides of the partition are lapped over the opposite faces of the downwardly projecting flange of the T bar. Preferably a filling strip 39 is employed to give the necessary thickness. The angles on both sides are 25 finished by means of angle moldings 29, identical with the moldings heretofore described and secured in place by the same means, namely, tap screws, or if preferred, rivets 40 may be used where it is possible to get at 30 both ends thereof. This same construction can, if desired, be used for securing the partitions to the sides of the car, in which event the T bar will be secured to the web of one of the side posts and will have one flange projecting inwardly, and having its leg in line 35 with the inner flange of the side post. This same construction can be used for connecting a metallic partition to any part of the car body. 40 The roof or top portion 22 of the compartments is formed of a plate 45 which has an opening therein for receiving the sash 46 when necessary for lighting the interior of the compartment. This plate has its upper 45 edge bent at an angle to its body as at 47 and secured by suitable tap screws or rivets 48 to the ventilator plate 10. The interior finishing sheet 49 is secured in place at the upper edge of this roof plate by simple moldings 50 and tap screws in the usual way. The lower edge of the plate 45 is curved downwardly as at 51 and the interior or partition finishing sheets 52 coming up from the floor are passed one on either side of said downturned portion 55. Preferably also a filling piece 53 is em-

ployed to give thickness to the partition. These finishing sheets are secured to the plate 45 by rivets 54 and grooved moldings 55. Preferably two such connections will be made, one at the extreme angle of the plate 70 45 so as to give a finish at the top, and another lower down and in line with the finish at the plate 6.

The construction above described is simple, gives a minimum number of parts, and especially provides a construction of light weight. It enables the use in a passenger car of any number of compartments built up entirely of metal, and in a manner to give a neat and ornamental finish and at a minimum weight. 80

What I claim is:

1. In a metallic railway car, the combination of the frame, a horizontal bar presenting faces at an angle to each other, a vertical inside finishing sheet applied to the vertical face of the bar, a horizontal interior finishing sheet applied to the horizontal face of the bar, a metallic angle molding finishing the corner and covering the edges of the finishing sheets, and means for securing the same to the transverse bar. 85

2. In a metallic railway car, the combination of a frame, a horizontal bar having faces at an angle to each other, vertical finishing sheets applied to the vertical face of the bar, a horizontal finishing sheet applied to the horizontal face of the bar, a metallic angle molding having portions at an angle to each other and fitting into the corner, each of said portions being grooved or recessed on the back and grooved on the face, and fastening means passing through the same and into the transverse bar and having the heads seated in the face grooves of the molding. 95

3. In a metallic railway car, the combination of an end frame, an end carline presenting a vertical face, an outside finish plate secured to the vertical face of the carline and the outer face of the end frame, a transverse bar providing a vertical face in line with the inner face of the end frame and with an inwardly extending horizontal face, vertical finishing sheets applied to the inside of the end frame and the vertical face of the transverse bar, horizontal inside finishing sheets applied to the horizontal face of the transverse bar and a metallic molding having portions at an angle to each other lapping over the edges of the finishing sheets and secured in place. 110 115

4. In a metallic railway car, the combination of an end frame, an end carline having a vertical face, outside finishing sheets applied to the outer face of the carline and of the end frame, a transverse bar having a vertical face in line with the inner edge of the end frame and a horizontal face extending toward the car center, a tie plate connecting the transverse bar to the end carline, vertical finishing 120 125 sheets applied to the vertical face of the transverse bar, and a metallic molding having portions at an angle to each other lapping over the edges of the finishing sheets and secured in place. 130

- sheets applied to the inside face of the end frame and vertical face of the transverse bar, horizontal finishing sheets applied to the horizontal face of the transverse bar, a metallic molding having portions at right angles and fitting over the edges of the finishing sheets and provided with face grooves, and securing means passing through the same into the transverse bar and having the heads seated in the face grooves of the molding.
5. In a metallic railway car, the combination of a frame, a bar having a web projecting into the car and having two faces at right angles to said web, one on either side of the web, partition sheets applied to either face of the projecting web of said bar, other finishing sheets applied to the two faces of the bar at right angles to the web, and a metallic molding applied in each of the angles and serving to cover the edges of the partition and finishing sheets.
6. In a metallic railway car, the combination of a frame having a member with a web transverse of the car body, a T bar riveted to said frame member and having a web projecting into the car body and presenting faces at right angles to said web, partition sheets applied to either face of the inwardly projecting web, and side finishing sheets applied to the faces at right angles to the web.
7. In a metallic railway car, the combination of a frame having a member with a web transverse of the car body and a flange on the interior edge longitudinal of the car body, a T bar riveted by one flange to the web of said frame member and having the other flange projecting inwardly and having its leg in line with the inside flange of the frame member, an interior finishing sheet applied to the inner flange of the frame member, a similar finishing sheet applied to the inner face of the leg of the T bar, and partition sheets applied to both faces of the inwardly projecting flange of the T bar.
8. In a metallic railway car, the combination of a frame member having a web transverse of the body and a flange on its inner edge, a T bar having one flange riveted to the web of the frame member and its other flange projecting into the car body and having its leg in line with the inner flange of the frame member, a finishing sheet applied to the inner flange of the frame member, a similar finishing sheet applied to the leg of the T bar, 55 a pair of partition sheets applied one to either face of the inwardly projecting flange of the T bar, and metallic moldings having portions at angles to each other and secured respectively on opposite sides of the inwardly projecting flange of the T bar and secured in place to said T bar and through the edges of the finishing and partition sheets.
9. In a metallic railway car, the combination of carlines, a ventilator plate secured thereto, and a partition top plate having its upper end flanged and riveted to the ventilator plate.
10. In a metallic railway car, the combination of carlines having lower deck members and vertical connecting members, a ventilator plate riveted to the vertical connecting members and provided with an out-turned flange at its lower edge, a compartment top plate having a flange at its upper end secured to the ventilator plate, and inside finishing sheets secured respectively to the flange of the top plate and the out-turned flange of the ventilator plate.
11. In a metallic railway car, the combination of a compartment top plate secured to the car side and having its inner edge turned downwardly, and vertical partition sheets lapped one on either side of the down turned edge of the top plate and secured thereto.
12. In a metallic railway car, the combination of a compartment top plate having one edge secured to the car side and having a free edge turned downwardly, vertical partition sheets lapped one on either side of the down turned edge of the top plate, a filling piece between the top plate and one of the sheets, and means securing the partition sheets to the top plate.
13. In a metallic railway car, the combination of a compartment top plate having one edge secured to the car side and having a free edge turned downwardly, vertical partition sheets lapped one on either side of the down turned edge of the compartment top plate, moldings covering the edges of the partition sheets, and securing means passing through the moldings and the sheets and the down turned edge of the compartment top plate.
- In testimony whereof, I the said ANDREW CHRISTIANSON have hereunto set my hand.
- ANDREW CHRISTIANSON.
- Witnesses:
- ROBERT C. TOTTEN,
J. R. KELLER.
